UNITED STATES PATENT OFFICE.

CHARLES A. HUNSTER, OF TACOMA, WASHINGTON.

CLOTHES-HANGER.

1,285,191.

Specification of Letters Patent. Patented Nov. 19, 1918.

Application filed April 13, 1917. Serial No. 161,863.

To all whom it may concern:

Be it known that I, CHARLES A. HUNSTER, a citizen of the United States of America, residing at Tacoma, in the county of Pierce 5 and State of Washington, have invented certain new and useful Improvements in Clothes-Hangers, of which the following is a specification.

The object of my invention is to provide a 10 clothes hanger to hang washed clothes in small places, such as kitchens, small laundries, bath rooms, and the like, and small rooms of apartment buildings.

Some parts of this country are subject to 15 frequent rains lasting weeks at a time, and it becomes quite a problem to hang the wash in rooms by the ordinary clothes line pins because of the fact that each garment of the wash takes up considerable space lengthwise 20 of the clothes line. This is true when the wash is hanging in rooms in the house as well as when hanging outside.

A further object of my invention is to 25 provide a clothes hanger of such construction that the garment may be fully extended to facilitate drying and at the same time require but a minimum space on the clothes line; and with these and other objects in 30 view my invention consists of the parts and combination of parts as will be hereinafter more fully set forth.

In the drawings:—

Figure 1 is a perspective view of a clothes hanger suspended on a clothes line embodying 35 my invention.

Fig. 2 is a top plan view of the same.

Fig. 3 is a front elevation of the same.

Fig. 4 is a sectional view on the line 4—4 of Fig. 2 looking in the direction of the 40 arrow.

The reference numeral 1 designates a clothes line of any approved type. My improved clothes hanger comprises a rigid bar 2 which may be made of wood, wire or any 45 other suitable material and may be of any desired length. 3 are trunnions extending from each end of the body 2 of the hanger, upon which are revolvably mounted suitable clasps 4 by means of which an article of 50 clothing 5 is suspended from the hanger and held in extended position so as to expose a maximum surface of the article of clothing to the drying action of the air and thereby hasten the process of drying. It 55 will be noted that these spring clasps 4 are journaled to the trunnions 3 near their upper

ends so that the clasps will hang normally in the position shown by reason of the greater weight thereof being below the trunnions.

In order that the article of clothing suspended from the clothes line 1 may require a minimum portion of the length of the clothes line, and thereby increase the capacity of the clothes line, and at the same time be securely suspended from the line 60 against accidental removal therefrom, I provide the bar 2 with a suspending hook of peculiar construction. This suspending hook comprises a single piece of wire 6 having a return bend 7 and 8 at each end, one return 65 bend, viz. 8, being positioned at a greater distance from the wire 6 than is the return bend 7, so that the loop between the return bend 8 and the wire 6 is wider than is the loop formed by the return bend 7, so that the 70 free ends of the wire, after the return bends are formed are in different vertical planes as shown in Fig. 2. The free end of the bend 7 is bent at right angles to form an extension 9 which is embedded in the bar 2 while 75 the free end of the bend 8 is bent at right angles as at 10 and adapted to pass through the bar 2 and is then again bent at right angles as at 11 and clamped to the underface of the bar 2 as shown in dotted lines 80 in Fig. 3.

As shown in Fig. 3 the body portion of the wire 6, intermediate the return bends, is deflected to one side of the point of attachment of the hook to the bar 2 and it will be seen 90 that the return bend 7 is substantially parallel with the body portion of the wire 6 while the return bend 8 is at an angle thereto, all of which is clearly shown in Fig. 3. The object of this angularity is that the hanger 95 is less likely to be accidentally disengaged from the clothes line, as such angularity resists any tendency of the hook to ride vertically of the rope on which it is suspended.

After the various bends, just above described are formed, the main portion 6 and the return bends 7 of the hook are bent upwardly in the arc of a circle as clearly shown in Figs. 1 and 4.

From the above it will be seen that I have 105 provided a cheap, simple, and effective clothes hanger.

What I claim is:—

In a clothes hanger the combination with a spreader bar upon which clothes may be 110 hung, of a suspension hook for the hanger comprising a single piece of wire bent up-

wardly in substantially crescent shape, and having an open return bend at each end, one bend being substantially parallel with the body of the hook while the other bend is at an angle thereto, whereby any tendency of the hanger to move upwardly relatively to the line on which it is suspended is resisted, the free ends of the return bends being bent

downwardly to serve as attaching means between the bar and the hook.

10

In testimony whereof I affix my signature in the presence of two witnesses.

CHARLES A. HUNSTER.
